UNITED STATES PATENT OFFICE.

SABIN SOLY AND IRENEE NAPOLEON SOLY, OF MONTREAL, QUEBEC, CANADA,
ASSIGNORS TO SAID IRENEE NAPOLEON SOLY.

OVERSEAMING-MACHINE.

1,043,161.

Specification of Letters Patent.

Patented Nov. 5, 1912.

Application filed February 23, 1904, Serial No. 194,677. Renewed September 18, 1911. Serial No. 649,820.

To all whom it may concern:

Be it known that we, SABIN SOLY and IRENEE NAPOLEON SOLY, both of the city of Montreal, Province of Quebec, Canada, have 5 invented certain new and useful Improvements in Overseaming-Machines; and we do hereby declare that the following is a full, clear, and exact description of the same.

Our invention relates to sewing machines, 10 and especially to the class used for the purpose of sewing fur.

The object of the invention is to provide simple and durable mechanism for forming a seam with a single thread, and mechanism 15 consisting of a series of initial operative members the constituent members whereof are effectually prevented from correlative displacement.

A further object of the invention is to enable parts for operating the looper to act 20 thereon as near as possible in a direct line with the axis thereof thus utilizing the maximum power of the operating part in the direct operation of the looper with minimum loss in side load.

The invention consists of a pair of single leader cams and an eccentric all made from a single piece of metal and in a homogenous mass, each member of this group merging in 30 that next to it.

A further feature of the invention consists of an oscillating crank effecting an operative connection between the connecting rod leading from the eccentric for reciprocating the looper, and the looper bearing, a further feature consisting of a universal ball joint forming a part of the operative connection between the pair of coacting single leader cams for oscillating the looper, and 40 the looper bar.

Another and an important feature of the invention consists in a particular construction and arrangement of parts which secures a forward movement of the cams and consequently the action thereof upon their followers at a point between the centers of rotation of the cams and the fulcrums of the followers.

Figure 1 is a longitudinal vertical section 50 of a machine constructed according to my invention. Fig. 2 is a plan, certain parts being broken away, as will appear, the cover of the machine being represented as removed. Fig. 3 is a vertical section supposed to have been taken substantially on the line

3-3 of Fig. 2, certain parts being represented as broken away. Fig. 4 is a section supposed to have been taken substantially on the line 4-4 of Fig. 2. Fig. 5 is a vertical section supposed to have been taken substantially on the line 5-5 of Fig. 2. Fig. 6 is a side elevation of a fork, which co-operates with a cam in connection with the looper movement. Fig. 7 is a rear elevation of the fork shown in Fig. 6. Fig. 8 is a horizontal section taken substantially on the line 8-8 of Fig. 1. Fig. 9 is a vertical section supposed to have been taken substantially on the line 9-9 of Fig. 8, this view being upon an enlarged scale, as will appear. Fig. 10 is a perspective representing a dog, which is used in connection with the feed mechanism; this view is upon an enlarged scale. Figs. 11, 12, 13, 14 and 15 represent the looper and needle in progressive 75 stages, co-operating to sew a seam.

Throughout the drawing and specification, the same numerals of reference denote like parts.

Referring more particularly to the parts, 80 1 represents the casing of a machine, which comprises a substantially rectangular or box-like base 2 adapted to be set upon a table or similar support, as will be readily understood; this base is provided forwardly 85 with a foot 3, under which is formed a pocket 4 containing certain feed mechanism, which will be described more fully herein-after. The casing 1 comprises also an upper section or body 5, which is attached rigidly 90 to the upper face of the base 2, as indicated at 6, and this body 5 is surmounted by a suitable cover 7 carrying certain parts, which will be referred to more fully herein-after.

In the lower portion of the body 5 there is rotatably mounted a transverse shaft 8, and substantially centrally upon this shaft there is rigidly carried an eccentric 9 of substantially circular form, as shown, and the hub of this eccentric preferably unites integrally, as shown, with a feed-cam 10. Immediately above the aforesaid eccentric 9, a needle-bar 11 is mounted, the same passing through guide openings 12 formed in the front and rear walls of the body, as indicated, and this needle-bar is adapted to be reciprocated through the medium of a fork 13 which is rigidly attached thereto, as shown, and which receives the eccentric, as 110

shown. This needle-bar is provided forwardly with a head 14, which is provided with means near its lower portion for attaching a needle 15, the said needle being disposed longitudinally with respect to the needle-bar, it being understood that the needle 15 reciprocates longitudinally in a substantially horizontal plane. It should now be stated that just beneath the needle 2, feed-wheels 16 and 17 are provided, the same being disposed in a substantially horizontal plane, and having toothed peripheries 18 intermeshing at a point 19 just beneath the path of the needle-point. The feed-wheel 17 is rigidly attached to the upper extremity of a spindle 20, which spindle is rotatably mounted near its upper extremity in a bracket-arm 21, which extends from the base 2, as shown. As the needle is reciprocated by the needle-bar 11, the spindle 20 is intermittently advanced in such a manner as to feed the seam being sewed at the point 19, the same passing between the intermeshing peripheries of the feed-wheels, it being understood that the feed-wheel 16 is maintained in contact with the feed-wheel 17 by mechanism which will be described more fully hereinafter.

For the purpose of actuating the feed-spindle 20, the aforesaid shaft 8 is provided with the aforesaid feed-cam 10, which cam has preferably substantially the outline shown in Fig. 1, the same cooperating with a feed-fork 22. This feed-fork is supported pivotally upon a link 23, being attached at the upper extremity of said link, the lower extremity of said link being pivotally attached at 24 to an arm 25 of an adjusting bell-crank lever 26. This adjusting lever is pivotally attached at 27 to the side wall of the base 2, as shown. The said bell-crank lever 26 is further provided with a wing 28 carrying a threaded stud 29, which stud projects through a curved slot 30 in the wall of the base, and carries a thumb-nut 31, as shown, the said thumb-nut affording means for locking the adjusting lever 26 in any position desired. Evidently, by fastening the adjusting lever in different positions, the fulcrum of the fork will be more or less elevated, in this manner effecting the throw or amplitude of movement of the lower extremity 32 of the fork. This lower extremity 32 is pivotally attached to an arm 55 of the bell-crank lever 33, the same being integral with an arbor 34, the extremities of which are pivotally mounted upon gudgeons 35, as indicated most clearly in Fig. 3. To the other arm of the bell-crank lever 33, a feed-rod 36 is pivotally attached, which feed-rod passes forwardly into the pocket 4, and attaches pivotally at its extremity to a feed-plate 37. This feed-plate 37 is loosely mounted upon the hub of the feed-disk 38, the same being mounted sub-

stantially centrally in the aforesaid pocket 4 and having a peripheral flange 39 projecting upwardly, as shown. Upon the flange 39 dogs 40 are received, the same consisting of short blocks having tapered inner extremities 41 and notches 42, which receive the said flange or rim, as indicated most clearly in Figs. 1 and 9. As shown, the dogs 40 project substantially radially inwardly and their inner extremities are engaged by shoulders 43, which shoulders are formed at the hub of the feed-plate 37; as indicated, there are preferably two of these dogs 40 placed oppositely, as shown. It being understood that the notches 42 fit snugly upon the rim 39, it will be evident that if a rotation of the plate 37 occurred in the direction of the arrow indicated in the full lines in Fig. 8, the shoulders 43 would tend to rotate the said dogs 40 upon their notches, in this manner causing them to bind upon the rim so that the movement of the feed-plate would be imparted to the feed-disk. When the return movement of the feed-plate 37 takes place in the direction of the arrow indicated in the dotted lines adjacent thereto, the dogs 40 are moved backwardly upon the rim 39 by small springs 44, the inner portions of which consist of coils 45 attached to the under face of the feed-plate 37, as shown. From the coils 45, the bodies of these springs 44 extend in the direction of the notches 42 of the dogs 40, and near their extremities are formed with lateral extensions 46, which press against the vertical faces of the dogs near the notches, as shown; and beyond the extensions 46, the springs terminate in extensions 47, which lie upon the upper faces of the dogs and slightly constrain the same downwardly. From this arrangement of the springs, it is evident that the force which returns the dogs 40 after they have had an advance movement presses upon the dogs very near the notches so that this force has little or no tendency to produce a rotation of the dogs; hence, there can be no binding action whatever in returning them, and consequently, the wear upon the faces of the notches is inappreciable. Such an arrangement as this is considered highly advantageous, for the reason that where the dogs have become slightly worn their efficiency is much diminished.

In order to prevent a retrogressive movement of the feed-disk 38, a detent dog 48 is employed, the same consisting of an elongated block having a notch 49 in the under edge thereof, which notch is adapted to be applied to the rim 39 like the notches 42 of the dogs 40. This detent dog is very clearly shown in Fig. 10, and its manner of application to the feed-disk is clearly shown in Fig. 8; it has a rounded nose 50 at its outer extremity, which abuts against a part of

the side wall of the pocket 4, as indicated; near the notch 49, the extremity of a spring 50^a presses the dog in a rearwardly direction with respect to the direction of rotation, the said spring comprising a coil 51 disposed about a stud within the pocket 4, as shown. The feed-disk 38 is rigidly attached to the spindle 20 by means of a key-plate 52, the same having an integral key 53 for this purpose, and attaching to the extremity of the spindle by means of a screw 54. It should be stated at this point that the operation of the feed-disk 38 with respect to the dogs 40 and 48 is much affected by the presence of oil by reason of the tendency for the parts to become gummed; in order to exclude the oil from these parts, which oil must be used copiously upon the other working parts of the machine, the rear wall of the pocket 4 is provided with a downwardly projecting lip 55, which constitutes an efficient shield for the purpose mentioned.

The feed-wheel 16 is rotatably carried upon a vertical extension 57 formed at the extremity of a presser-bar 58, which presser-bar has a downwardly disposed extension 59 passing under the said feed-disk, as shown. The body of this bar 58 is disposed substantially parallel with the needle-bar 11, the same having a flattened portion 59 passing through an opening or notch 60 formed in the forward wall of the body 5. The said presser-bar is held in this notch by means of a plate 61, disposed as shown most clearly in Figs. 2 and 5. Except for the portion 59 referred to, the bar 58 is preferably of round form, as shown. Its inner portion, which lies within the casing, is surrounded by a helical spring 62, which thrusts against a transverse pin 63, so as to constrain the feed-wheel 16 against the feed-wheel 17, as will be readily understood; for the purpose of enabling the feed-wheel 16 to be moved away from the feed-wheel 17 to facilitate the insertion of the seam to be sewed, the inner extremity of the feed-bar 58 is pivotally attached to an arm 64, which arm is rigidly carried by an arbor 65, the said arbor having another arm 66, which projects rearwardly through an opening in the casing and is provided at 67 with facilities for attaching a treadle link or similar operating means. From this arrangement, it should be understood that by forcing the arm 66 upwardly, the arm 64 would be forced forwardly, so as to compress the spring 62 and displace the wheel 16 in a forward direction.

To the extremity of the aforesaid extension 57, just above the face of the feed-wheel 16 there is rigidly attached a needle-plate 68 having a groove 69 in the upper face thereof, constituting a guide for the needle 15, as will be readily understood, and just above the needle-plate 68 there is attached a looper-plate 70 having an edge 71 disposed

toward the point 19, which edge facilitates the formation of the loop, in a manner which will be described more fully herein-after.

Directly above the needle-bar 11, a looper-bar 72 is mounted, the same comprising a head 73 rigidly attached to a stem 74, which stem is longitudinally slideable in a rocker guide 75, the said guide being supported upon the side walls of the body 5 through the medium of gudgeons 76. Behind the head 73, the said stem carries in rotary relation therewith a sleeve 77 comprising a cap 78, as shown, which cap co-operates with the said sleeve to form a bearing for a crank-pin 79, the said pin being made integral with the arms of a crank 80, as shown; as indicated most clearly in Fig. 5, this crank 80 is supported at the left upon a gudgeon 81, and at the right upon a gudgeon 82, that extremity which cooperates with the gudgeon 82 comprising an elongated shank 83. Upon this shank 83, an arm 84 is attached rigidly, a set-screw 85, and a through-pin 86 being used in this connection. This arm 84 is for the purpose of enabling the crank 80 to be rocked to and fro; for this reason, the arm 84 is connected pivotally with an eccentric-rod 87, the lower extremity whereof attaches to an eccentric 88, which includes 95 an eccentric sheave, the same being rigidly carried by the aforesaid shaft 8. From this arrangement, when the shaft 8 rotates, the eccentric-rod 87 operates to rock the crank 80 to and fro, which has the effect of 100 giving the looper-bar a reciprocating movement; when this movement is taking place, it will, of course, be understood that the forward portion of the looper-bar rises and falls to a small extent, this movement being 105 permitted by reason of the pivotal bearing of the guide 75.

In addition to the longitudinal reciprocating motion of the looper-bar, this bar is given a reciprocating axial movement, for 110 a purpose which will appear more fully herein-after. To this end, the stem 74 carries rigidly a rocking-sleeve 89, the same having a transversely disposed head 90 in which is rotatably mounted a pin 91, and this pin has a bifurcated extremity 92, in which is pivotally attached the upper extremity of a rod 93; this rod is actuated by a fork 94 having an integral pivotally mounted arbor 95; the said fork having an 120 extension 96 facilitating the attachment of the said arm 93, as indicated. The fork 94 is peculiarly constructed, inasmuch as the tines 97 and 98 thereof are off-set laterally with respect to each other, and these tines 125 co-operate respectively with cams 99 and 100 cast in one piece and secured to shaft 8 by means of a hub 101. In this connection, it should be understood that the cam 99 operates to elevate the fork, and the cam 100 130

operates to move the same downwardly, and the said cams are so designed with relation to each other that they are always in contact with their respective tines, from which arrangement there is never any slack or lost motion at this point. Such an arrangement as this is considered highly advantageous, for the reason that it does away with the necessity for springs, which are sometimes employed in connection with cams to maintain the actuated member in contact with the face of the cam; where the movements are very rapid, such a spring must, of necessity, be of considerable power in order to enable the parts to act quickly, and the incessant pressure upon the cam-face produces considerable friction and undesirable wear of the parts. It should now be understood that when the shaft 8 is rotated, the needle-bar will be reciprocated at the same time the looper-bar will be reciprocated thereabove; however, the reciprocation of the looper-bar will be a compound one involving a reciprocation upon its own axis.

In the forward extremity of the head 73 of the looper-bar, a looper-finger 102 is attached, the same being preferably of substantially the form shown, curving downwardly so that its extremity lies normally adjacent to the path of the needle 15, as indicated most clearly in Fig. 1. This finger is provided at its extremity with a point 103, which projects laterally, as shown, and opposite to this point there is a heel or nib 104. In Fig. 11, this finger 102 is represented as having caught a loop 105 formed near the needle-point holding the same preparatory to having the needle pass therethrough, the said loop being caught over the point 103, and passing under the heel or nib 104. The needle passes close to the nib 104, as indicated in Fig. 11. In Fig. 12, the stitch is represented in a more advanced stage, the looper having passed away from the needle and upwardly, so as to disengage it from the loop. In Fig. 13 the needle is represented just in the act of forming the loop, which is made at the looping-edge 71; after catching the loop over the looping-point 103, the looper-bar moves rearwardly at the same time that the finger moves upwardly, so that as the needle is withdrawn from the seam, the finger draws the loop (which it catches beyond the seam) toward the front of the seam, and it is then immediately moved into a depressed position, such as shown in Fig. 11 to allow the needle to pass through the loop. In connection with these Figs. 11 to 15, 106 represents the seam, 107 represents the thread which is forming the seam. It should be understood that the arm 84 will be set at a very accurately adjusted angle, in order to facilitate the nice coöperation of the looper-finger with the needle. In practice the correct

position and adjustment would be obtained by means of the said screw 85, and after the proper position has been obtained, the pin 86 would be inserted, permanently fixing the parts in their best relation.

Upon the cover 7, a spool 108 is mounted, and the thread passing therefrom passes around a guide-stud 109, and then around a portion of the periphery of a tension-pulley 110, thence passing through a guide-eye 75 111, and around a needle-bar guide 112 and thence to the end of the needle, which is located, as shown, near the point of the same. The machine may be continuously driven by means of a belt-pulley 113, and the shaft 8 may carry, at another point, a balance-wheel 114 adapted to make the rotation of the machine uniform.

In operation, it should be understood that the pieces to be united would be superposed 85 and fed horizontally between the feed-wheels 16 and 17, so that the alining edges would project slightly above the edges of the feed-wheels, as will be readily understood. A guide 16^a, which consists of a curved finger 90 terminating at the point 19 is arranged for the purpose of assisting the guiding of the material.

The main advantages of an overseaming machine constructed according to the foregoing are as follows:—Owing to the looper bar being located beneath and suspended from the crank pin of its operating crank shaft, such looper-bar is brought more closely to the level of the needle, thus enabling a shorter looper finger to be used with less vertical motion to perform its function, and consequently less spring of the looper-bar and finger and less lost motion. The effect of this is that the looper finger can 105 be adjusted to work closer to the needle and finer and more uniform work is produced. Owing to the particular relative arrangement of the cams and their coöperative parts, our improved machine in running 110 causes the cams, when imparting stitch forming motions to the stitch forming instrumentalities, to act upon the portions of the forks between the centers of rotation of the cams and the fulcrum points of the 115 forks, with the result that the power of the cams is applied to the instrumentalities more directly than heretofore while there is less spring (and, consequently, lost motion) between the cams and forks. A further advantage is that the group of the looper operating parts (the two single leader cams and eccentric) are made positively and invariably coöperative. Heretofore these parts (or such of them as have 125 been utilized) have been secured independently of one another to their carrying shaft. Usually the eccentric, one single-leader cam, and a spring coacting with the cam have performed, imperfectly, the functions of our 130

group of operative parts, and the eccentric and cam have frequently after having been set (in the assembling of the machine), shifted their relative angular position, 5 which, of course, resulted in the breakage of either the needle or the looper finger. We obviate any chance of this breakage by casting all the looper actuating parts (the two single-leader cams and the eccentric) in 10 one piece.

Our particular arrangement of the cams and their followers which causes the cams to act upon the portions of the followers nearest to the parts to which the followers are 15 operatively connected, is as follows:—The rotation of the cam shaft 8 is forward. That is to say, the top of the shaft travels toward the front of the machine. The resultant operative movement of the eccentric 20 9 and cam 10 (Fig. 1) and eccentric 88, and cams 99 and 100 (Fig. 4) is such that each of the eccentrics and cams exert their power, when causing the instrumentalities to 25 perform their functions, upon the portions of their particular followers nearest to the instrumentalities they operate. The particular relative angular positions of these eccentrics and cams are as shown in Figs. 1 and 4 both of which depict the cam shaft 30 8 in the same position in relation to the operation of the machine. By referring to Fig. 1 it will be observed that the eccentric 9, in the performance of its function of inserting the needle into the work, acts upon 35 the portion of the forward tine of the fork 13, nearest to the crotch of such fork, and it bears upon the outer end of the rear tine only to withdraw the needle from the work. The same action is effected by feed cam 10 40 upon fork 22, by eccentric 88 upon rod 87, and by cams 99 and 100 upon the tines 97 and 98 of fork 94 coacting with the eccentric 88 in the operation of the looper. We would particularly point out here that the 45 relative angular positions of the cams 99 and 100 and the eccentric 88 constitute an important feature of this invention. By means of this particular arrangement each member of the group exerts its power stroke 50 upon its follower in a way to obviate any chance of the latter springing (as would occur if the power stroke were exerted upon the ends of the tines) and consequently the parts interfering and being 55 broken as heretofore pointed out.

In all sewing machines the needle bar, or carrier, is in great need of true and comparatively powerful actuation owing to the fragile nature of the needle and its work in 60 perforating the stock being stitched. Our

particular arrangement of the eccentric 9 and the fact of its bearing as close as possible to the true axial plane of the needle bar insures the required true action and at the same time (as is the case with all the 65 cams and the other eccentric of our machine) applies the energy of the eccentric with the least loss, to the needle bar.

While I have shown in the accompanying drawings the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims, or of mechanical equivalents to the structures set forth.

Having described my invention what I 80 claim and desire to secure by Letters-Patent, is:—

1. In a sewing machine the combination with a straight needle and a looper coacting therewith, of a crank shaft with its crank 85 pin disposed above the axis of the crank shaft, means operatively connected directly to the crank-shaft for oscillating the same and through it such looper longitudinally to the needle, a looper bar located with its axis 90 at right angles to and intersecting the axis of the crank shaft when the crank is in its uppermost position, a sleeve mounted upon the bar, a cap secured upon the sleeve and together therewith inclosing the crank pin, 95 and means whereby the looper is connected to the looper bar.

2. In an overseaming machine, looper mechanism, comprising a pair of upwardly projecting arms 80 connected rigidly together near their upper ends by a crank pin 79, one arm having a laterally projecting elongated shank near its lower end, and the end of the shank and the other arm having a pair of sockets in axial alinement, a pair 100 of gudgeons carried by stationary parts of the machine and engaging the said sockets, a looper bar, a member located between the lower ends of the said arms 80 and hung from the said crank pin the said member 105 being adapted to support the bar, means for oscillating the said shank, and a looper finger carried by one end of the said bar.

In witness whereof we have hereunto set our hands in the presence of two witnesses. 115
